(Cl. D90—8)

To all whom it may concern:

Be it known that I, Corradino d'Ascanio, a citizen of Italy, residing at Pisa, Italy, have invented a new, original, and ornamental Design for Motor Bicycle, of which the following is a specification, reference being had to the accompanying drawings, forming part thereof.

Figure 1 is a side elevational view of a motor bicycle, showing my new design;

Figure 2 is a perspective view of the same looking towards the front;

Figure 3 is a perspective view of the motor bicycle looking towards the rear and the side, shown in Figure 1; and

Figure 4 is a rear and side perspective view opposite that shown in Figure 3.

I claim:

The ornamental design for a motor bicycle, as shown.

CORRADINO D'ASCANIO.
